PACKAGE OF SLICED FOOD OR THE LIKE

Oscar E. Seiferth and Glenn M. Austin, Madison, and Maurice J. Gifford, Monona, Wis., assignors to Oscar Mayer & Co., Inc., Chicago, Ill., a corporation of Illinois

Filed Sept. 9, 1966, Ser. No. 3,801

Term of patent 14 years

(Cl. D9—192)

The essential features of our design reside in the portions shown in full lines.

The package is characterized by the combination of a quantity of a product enclosed in a container having a cylindrical body with vertical and horizontal ribs in the side wall thereof and a closure forming base with a raised panel portion on which the product is supported.

We claim:

The ornamental design for a package of sliced food or the like, substantially as shown and described.
